UNITED STATES PATENT OFFICE.

CHARLES T. McCARROLL, OF OTTUMWA, IOWA.

DESIGN FOR A WOOD-HOD.

SPECIFICATION forming part of Design No. 32,491, dated April 10, 1900.

Application filed February 19, 1900. Serial No. 5,864. Term of patent 14 years.

To all whom it may concern:

Be it known that I, CHARLES T. McCARROLL, a citizen of the United States of America, and a resident of Ottumwa, Wapello county, Iowa, have invented and produced a new and original Design for a Wood-Hod, of which the following is a specification.

The object of my invention is to provide a new, useful, original, and ornamental design for receptacles or carriers whereby to convey stove-wood and similar fuel.

My invention consists of the design herein-after set forth, pointed out in my claim, and illustrated by the accompanying drawings, in which—

Figure 1 is a perspective of a wood-hod, illustrating my design. Fig. 2 is a vertical cross-section of the same.

In the design as illustrated the numeral 10 designates the body, generally of concavo-convex form. The body 10 is of generally oblate form and curved on its shortest diameter, having straight parallel sides and rounded ends opposite each other. The body 10 is 25 corrugated or beaded on lines concentric with the margins thereof. The lines of corrugations or beads are partially straight longitudinally of the body and partially circular concentric with the rounded ends of the body.

The straight portions of the corrugations or beads are parallel. An arched handle 11 extends from the center of one of the rounded ends of the body 10 upwardly and across the body in an arc and to the center of the opposite rounded end of the body. The handle 11 is concavo-convex in cross-section and has its concaved face farthest from the concaved face of the body except at its ends, which end portions of the handle are flattened at the junction thereof to the ends of the body 10. A curved bar 12, having convolute or bent end portions 12^a 12^b, extends longitudinally of that portion of the body 10 within the central corrugation or bead and beneath the body, and the convolute end portions extend tangentially from the lower face of the body and have their outermost points approximately in alignment with the outermost point of the bar.

I claim as my invention—

The design for a wood-hod, substantially as herein shown and described.

Signed by me at Ottumwa, Iowa, this 20th day of December, 1899.

C. T. McCARROLL.
